CEMENT SHOE

Application filed December 17, 1930. Serial No. 503,016.

This invention is a cement shoe for well casing and the like; the present invention being an improvement upon the cement shoe disclosed in my copending application Ser. 5 No. 490,712, filed October 23, 1930.

In my aforementioned copending application I have disclosed a cement shoe suspended from well casing and adapted to float the casing into a well and discharge a circulating medium outwardly through the bottom of the shoe, with said shoe having a seating surface in spaced relation above said discharge means adapted to engage the formation seat of the well bore, and providing for subsequent discharge of the circulating medium outwardly through the shoe both below and above the point at which it engages the formation seat; and the present invention functions in the same general manner but insures discharge of 15 the circulating medium longitudinally from the lower end of the shoe so that the full force of the circulating medium is directed against any obstruction which may be encountered when floating the string of casing into a well.

The present invention also provides for directing the circulating medium outwardly through the shoe above the point at which it engages the formation seat, only after all of 20 said circulating medium has been discharged longitudinally outwardly through the lower end of the shoe for insuring any obstruction being washed away; and the invention also provides extremely simple means for redirecting the circulating medium which is longitudinally discharged from the lower end of the shoe, so that after the shoe engages the formation seat the circulating medium is readily discharged outwardly through the shoe above the point of said seating engagement.

It is a still further object of the invention to circumferentially equalize the distribution of the circulating medium as it discharges from the shoe above the point at which it engages the formation seat, and after initial

discharge of the circulating medium from the lower end of the shoe to redirect the same for discharge above the point of seating engagement of the shoe, so that when the circulating medium comprises a cementing mixture adapted to cement the casing in the well, the said cement will positively hold the shoe against turning in the well and will thus permit the shoe being readily drilled out when drilling is resumed.

Further object of the invention will be readily understood from the following description of the accompanying drawings, in which:

Fig. 1 is an axial section through a well bore showing the cement shoe suspended from a casing string.

Figs. 2 and 3 are transverse sections on the lines 2—2 and 3—3 respectively of Fig. 1.

The cement shoe is adapted for suspension from a usual string of well casing 1, preferably by a usual threaded connection 2, and the casing string with its suspended shoe is adapted to be run into a well bore 3 having a usual formation seat 4 and a depending rat-hole 5.

The casing shoe preferably comprises an annulus 6 having a collar 7 at its upper end providing the threaded connection 2 for the casing string, with a nipple 9 depending from the lower end of annulus 6, preferably by a threaded connection 10, and forming an exterior tapering seat 8 adapted to engage the formation seat 4 and merging into a depending annulus 9a of reduced diameter 75 which is adapted for reception in rat-hole 5, and which preferably terminates in a bull-nose 11 for guiding the casing string into the well bore.

An axial port 12 opens through the bull-nose 11, and discharge ports 13 are provided in the annulus 6 above the tapering seat 8; and the shoe is provided with guide means adapted to direct a washing medium or fluid cement which is forced downwardly through

the casing string, so that the fluid initially flows downwardly without discharge at ports 13 and is discharged longitudinally through axial bore 12, and when the rat-hole has been 5 filled with cement and the seat 8 engages the formation seat 4, the cement which has been discharged through bore 12 is redirected upwardly into the shoe so that it flows past the seating engagement 4-8 and is then discharged through the ports 13 into the surrounding well bore above the formation seat.

As an instance of this arrangement a filler 15, preferably of cementitious material, may be cast in the cement shoe so as to fill and extend upwardly from the nose 11 to a point spaced above the discharge ports 13, with the filler extending radially to the wall of annulus 6 and depending nipple 9, so that a restricted axial bore 16 which opens through 10 the filler is shut-off from communication with ports 13 but directly aligns with and is open to port 12. The depending annulus 9a has circumferentially spaced longitudinal grooves 17 in its outer surface, merging at 15 their lower ends into the bull-nose 11 and terminating at their upper ends below tapering surface 8 so as to form undercut recesses 18; and longitudinal bores 19, which are radially spaced from bore 16, open through the filler 15 from the recesses 18 to an annular groove 20 which is formed in the outer periphery of the filler 15 in alignment with ports 13. It will thus be seen that only after longitudinal discharge of a circulating medium 20 through port 12 and into the well bore, can said circulating medium return through grooves 17 and bores 19 for discharge at ports 13.

A valve is preferably provided in the cement shoe for controlling communication of bore 16 with the bore of casing string 1, and is adapted to close during lowering of the casing string so as to float the string into the well bore in usual manner, and is adapted to 40 open responsive to the pressure of fluid forced downwardly through the casing string so as to longitudinally discharge all of said fluid via bore 16 through the port 12.

As an instance of the float valve construction a supporting annulus may be mounted 50 in an annular recess 16a which is formed in the upper end of bore 16, and the supporting annulus preferably comprises a cylindrical sleeve 22 internally flanged at its upper end so as to form a valve seat 23 in alignment with bore 16, with an annular extension 24 preferably threaded into the lower end of sleeve 22 and forming an axial guide 25 for a valve stem, with the guide 25 surrounded 55 by longitudinal discharge passageways 26 communicating with the lower portion of bore 16. A valve 27 has a stem 28 slideable in guide 25 so that the valve 27 is adapted to engage seat 23, and a spring 29 preferably 60 surrounds the valve stem and abuts at its

respective ends against the underside of the valve and the upper face of the guide so as to tend to close the valve while permitting opening thereof by yielding of the spring responsive to pressure in the bore of the string of well casing above the valve. The spring 70 29 when compressed limits downward movement of the open valve so that it does not close the passageways 26 but permits free flow past the open valve and through said passageways 75 into the lower portion of bore 16.

After the string of well casing and its depending shoe have been cemented in the well bore, the shoe may be drilled out so that drilling of the well may be resumed, and for this purpose the float valve structure and the entire nipple 9 are preferably of material such as aluminum which may be readily cut away; and the cement, which surrounds the depending annulus 9a of the nipple, by filling the 80 grooves 17 will positively hold the nipple against turning, so that the cementitious filler 15, together with the float valve and depending nipple, may be readily drilled out in usual manner.

In operation the cement shoe is suspended from casing 1, and with valve 27 closed by its spring 29 the string of casing is lowered into a well bore. The well pressure against the valve then retains it in closed position so that the string may be floated into the bore, and a usual washing medium may be circulated downwardly through the casing string and outwardly into the well bore, with the 90 pressure of the circulating medium shifting the float valve to its open position so that the washing medium may freely flow through bore 16 and thence longitudinally outwardly through the port 12 of bull-nose 11 so that the full pressure of the circulating medium is 100 directed against any obstruction in the well bore.

When the well is to be cemented, a usual fluid cement is similarly forced downwardly through the casing string so as to open the float valve and thence flow downwardly through bore 16 for discharge through port 12 into the surrounding well bore, and when the rat-hole surrounding the depending nipple of the cement shoe has thus been cemented-off, seat 8 of the cement shoe is rested on formation seat 4, so that further flow of cement discharged through port 12 is forced upwardly at the exterior of annulus 9a and through longitudinal grooves 17 and bores 19 into the circumferential groove 20 for uniform distribution and discharge through ports 13 into the surrounding well bore above the formation seat.

The invention thus provides an extremely 120 practical cement shoe for a casing string, adapted to anchor on the formation seat of a well bore with a depending nipple adapted to extend into the rat-hole, and the shoe being arranged so as to insure direct longitudinal

discharge of a circulating medium outwardly through the lower end of the shoe for washing away any obstruction, with the shoe then adapted to seat on the formation seat of the 5 well bore, and redirecting the discharged circulating medium upwardly at the exterior of the depending nipple of the shoe and thence upwardly through the shoe for discharge into the surrounding well bore above the formation seat; and the invention also provides for 10 operatively supporting a float valve in the cementing shoe, with the valve structure and the depending nipple of the shoe adapted to be readily drilled-out after the casing is 15 cemented in the well.

I claim:

1. In combination, a shoe for a casing string having an exterior seating surface adapted to engage the formation seat of a 20 well bore and having a depending nipple adapted to extend into the rat-hole below the formation seat, a discharge port in the nipple below said seating surface, a discharge port in the shoe above said seating surface, 25 means for closing the bore of the shoe against communication with the upper discharge port and discharging fluid from said bore through the lower discharge port, and means for redirecting said discharged fluid upwardly 30 through the shoe for discharge at the upper discharge port.

2. In combination, a shoe for a casing string having an exterior seating surface adapted to engage the formation seat of a 35 well bore and having a depending nipple adapted to extend into the rat-hole below the formation seat, a discharge port in the nipple below said seating surface, a discharge port in the shoe above said seating surface, means 40 for closing the bore of the shoe against communication with the upper discharge port and discharging fluid from said bore through the lower discharge port, and means separate from said bore of the shoe for redirecting said 45 discharged fluid upwardly through the shoe for discharge at the upper discharge port.

3. In combination, a shoe for a casing string having an exterior seating surface adapted to engage the formation seat of a well bore and 50 having a depending nipple adapted to extend into the rat-hole below the formation seat, a discharge port in the nipple below said seating surface, a discharge port in the shoe above said seating surface, means for closing 55 the bore of the shoe against communication with the upper discharge port and discharging fluid from said bore through the lower discharge port, and a passageway closed to said bore of the shoe and opening to the exterior 60 prior of the nipple and adapted to redirect the discharged fluid upwardly through the shoe for discharge at the upper discharge port.

4. In combination, a shoe for a casing string having a discharge port at the lower end and 65 a discharge port spaced above said lower dis-

charge port, means for closing the bore of the shoe against communication with the upper discharge port and discharging fluid from said bore through the lower discharge port, and means separate from said bore of the shoe for redirecting said discharged fluid upwardly through the shoe for discharge at the upper discharge port. 70

5. In combination, a shoe for a casing string having a discharge port at the lower end and a discharge port spaced above said lower discharge port, means for closing the bore of the shoe against communication with the upper discharge port and discharging fluid from said bore through the lower discharge port, 75 a float valve for the bore of the shoe, and means separate from said bore of the shoe for redirecting said discharged fluid upwardly through the shoe for discharge at the upper discharge port. 80

6. In combination, a shoe for a casing string having an exterior seating surface adapted to engage the formation seat of a well bore and having a depending nipple adapted to extend into the rat-hole below the formation seat, a discharge port in the nipple below said seating surface, a discharge port in the shoe above said seating surface, means for closing the bore of the shoe against communication with the upper discharge port and discharging 90 fluid from said bore through the lower discharge port, a float valve for the bore of the shoe, and means for redirecting said discharged fluid upwardly through the shoe for discharge at the upper discharge port. 95

7. In combination, a shoe for a casing string having an exterior seating surface adapted to engage the formation seat of a well bore and having a depending nipple adapted to extend into the rat-hole below the formation seat, a discharge port in the nipple below said seating surface, a discharge port in the shoe above said seating surface, means for closing the bore of the shoe against communication with the upper discharge port and discharging 100 fluid from said bore through the lower discharge port, the outer surface of the nipple having a longitudinal groove terminating at its upper ends in an undercut recess at the lower end of the seating surface, and a passageway in the shoe closed to the bore of the shoe and opening to the exterior of the nipple at said recess and adapted to redirect the discharged fluid upwardly through the shoe for discharge at the upper discharge port. 110

8. In combination, a shoe for a casing string having an exterior seating surface adapted to engage the formation seat of a well bore and having a depending nipple adapted to extend into the rat-hole below the formation seat, a discharge port in the nipple below said seating surface, a discharge port in the shoe above said seating surface, means for closing the bore of the shoe against communication with the upper discharge port and discharg- 125

ing fluid from said bore through the lower discharge port, a float valve for the bore of the shoe, the outer surface of the nipple having a longitudinal groove terminating at its upper ends in an undercut recess at the lower end of the seating surface, and a passageway in the shoe closed to the bore of shoe and opening to the exterior of the nipple at said recess and adapted to redirect the discharged fluid upwardly through the shoe for discharge at the upper discharge port.

In testimony whereof I have affixed my signature.
